UNITED STATES PATENT OFFICE.

ALFRED H. BARTSCH, OF SPRINGFIELD, MASSACHUSETTS, AND MARCUS C. HOPKINS, OF WASHINGTON, DISTRICT OF COLUMBIA; SAID BARTSCH ASSIGNOR TO AMERICAN BOSCH MAGNETO CORPORATION, OF NEW YORK, N. Y., A CORPORATION OF NEW YORK, AND SAID HOPKINS ASSIGNOR TO HOPKINS CORPORATION, OF JERSEY CITY, NEW JERSEY, A CORPORATION OF DELAWARE.

LOUD-SPEAKER.

Application filed February 5, 1926. Serial No. 86,123.

This invention relates to loud speakers and particularly to that type which embodies the use of a large conical diaphragm.

The diaphragm of cone type loud speakers 5 is usually made of some fibrous material such as paper, impregnated cloth or the like. We have discovered that a conical dia- 10 phragm constructed at least partly of thin wood produces superior results. For in- stance, a conical diaphragm so constructed gives a very pleasing, soft and mellow tone to the reproduced sound. Moreover, the appearance of the loud speaker is greatly improved.

15 In accordance with our invention we em- 20 ploy thin wood veneer in the construction of the diaphragm. We have found the Japanese wood veneer is well suited for the purpose. This veneer is obtainable in the form of thin sheets of wood ranging from about .00075 of an inch to about .001 of an inch in thickness, cemented to a tissue paper 25 backing of about the same thickness, making the total thickness of the layer of wood and the backing range from about .0015 of an 30 inch to .002 of an inch. Japanese wood veneer is so thin that a diaphragm constructed of it would not be self-supporting unless an impractical number of layers were 35 used. We, therefore, apply the veneer to a fibrous support or filler such as manila paper or craft paper by cementing one or more layers of the Japanese veneer to either one or both sides of the paper support in the 40 manner hereinafter described more in detail. The composite sheet thus produced is formed into a cone preferably by cutting a sector from it and then folding the sheet to conical form and uniting the radial seam by gluing, stitching or the like.

One form of loud speaker constructed in accordance with the invention is illustrated in the accompanying drawings, in which:

45 Figs. 1 to 3 are respectively a front ele- vation, a side elevation and a rear elevation of the loud speaker;

Fig. 4 is a vertical transverse section of the speaker, and

50 The remaining figures are alternately frag- mentary sections and perspective views illustrating various ways in which the wood veneer may be applied to the paper support.

The type of speaker disclosed in the drawings comprises a conical diaphragm 1 secured at its edge portion to the periphery of a 55 dished sheet metal member 2. The sheet metal member 2 is in turn supported by a pedestal 3. The electromagnetic mechanism for actuating the cone is denoted in general at 4 and is preferably attached to and carried by a plate 5 (Fig. 4) which is secured to the back of the sheet metal member 2 and constitutes a closure for a central opening 6 provided in the sheet metal member 2. The electromagnetic mechanism includes a rod 65 6, which is clamped to the apex of the conical diaphragm 1 by means of a set screw 7.

The general features of the construction so far described form no part of the present invention, but are covered in various pending applications of Marcus C. Hopkins. The present invention pertains more particularly to the diaphragm per se, and to a loud speaker of general characteristics having a diaphragm of the particular construction 75 herein disclosed.

The preferred way of constructing the diaphragm is to employ a sheet of manila or craft paper and to cement or glue the Japanese wood veneer to the sheet of paper 80 in any one of the various ways illustrated in Figs. 5 to 8^a inclusive.

According to Figs. 5 and 5^a the Japanese wood veneer is applied to only one side of the paper support. In these figures the 85 paper support is indicated at 8 and the Japanese wood veneer at 9 and 9', 9 being the wood veneer proper and 9' being the tissue paper backing to which the veneer proper is cemented. The combined sheet 90 including the veneer 9 and the tissue paper backing 9' is glued directly to one face of the paper support 8. When only one layer of the veneer is employed the grain of the veneer may run in any direction. Fig. 95 5^a shows in perspective a portion of the paper support 8 with the superposed layers of wood veneer 9 and tissue paper backing 9'; and this figure also shows the graining on the veneer at 10.

In Figs. 6 and 6^a two layers of the Japanese veneer are glued to one face of the paper support 8. The sheets of Japanese wood veneer are preferably disposed back

to back, that is, with the tissue paper backing 9' of one sheet abutting the tissue paper backing of the other sheet. The two sheets of Japanese veneer may be cemented or 5 glued to each other and then glued to the paper support 8, or one sheet of the Japanese wood veneer may be glued to the paper support and then the other sheet of Japanese veneer glued to the sheet first applied. 10 Where two sheets of veneer are employed as in Fig. 6, it is preferable, though not essential, to apply the sheets of veneer to the paper support in such a way that the grain of one sheet is disposed at an angle, preferably at a right angle, to the grain of the other sheet. This is represented in Fig. 6^a in which it will be noted that the grain 10 of one sheet of the veneer is disposed at right angles to the grain 10 of the other sheet. 15 20 In Fig. 7 a sheet of Japanese veneer 9, 9' is applied to each face of the paper support 8. In this case it is also preferable, though not essential, to have the grain of one sheet of veneer at right angles to the grain of the other sheet of veneer as indicated in Fig. 7^a.

In Fig. 8 two sheets of veneer 9, 9' are applied to each face of the paper support 8 and preferably the two sheets of veneer on 30 each side of the paper support 8 are placed back to back as described in connection with Fig. 6. The same system of applying the veneer to the paper support 8 may be followed as described in connection with Fig. 35 6. That is, the veneer sheets at each side of the paper support 8 may be cemented or glued in place successively or the two sheets at one side of the paper support 8 may be first glued or cemented together and then 40 applied to the paper support. When two sheets of veneer are employed at each side of the paper support as in Fig. 8, the grain of the two sheets on one side of the paper support may run in the same direction and 45 be disposed at right angles to the grain of the two sheets at the other side of the paper support. Preferably, however, the sheets of veneer are so applied that the grain of each sheet runs at right angles to the grain of the 50 next adjoining sheet as illustrated in Fig. 8^a. However, if the grains of the two sheets at one side of the paper support 8 are at right angles it is probably immaterial whether the 55 grains of the two inside sheets adjacent the paper support 8 are at right angles with respect to each other or in the same direction.

Any number of sheets of veneer may be applied either to one or both sides of the paper support following the various methods 60 outlined above, provided the total thickness of the composite diaphragm does not exceed practical limits.

As above stated the wood veneer which we employ is so thin that a diaphragm con-

structed of it would not be self-supporting 65 unless an impractical number of layers were used. For this reason, it is desirable to use the filler or paper support 8. We have found that the best results are obtained by using one layer of Japanese veneer at each 70 side of the paper support 8, this being the arrangement disclosed in Figs. 7 and 7^a. The thickness of the paper support which we prefer to employ ranges from about .007 to .008 of an inch making the total thickness 75 of the composite diaphragm shown in Figs. 7 and 7^a range from about .01 of an inch to about .012 of an inch.

By employing two sheets of wood veneer and so disposing them that the grain of one 80 runs at right angles to the grain of the other, the tendency of the diaphragm to warp is reduced to a minimum in spite of its thin character.

A diaphragm constructed as above described may be mounted in the sheet metal member 2 by providing the diaphragm near its outer edge with a circumferential crease 11 to form a forwardly flaring brim portion 12. The sheet metal member 2 is provided with a corresponding offset forwardly flaring brim portion 13 on which the brim 12 of the diaphragm seats and to which it is preferably glued or cemented. However, the brim 12 of the diaphragm should not 95 seat over its entire width on the sheet metal member 2 otherwise the conical portion of the diaphragm would not be sufficiently free to vibrate axially. The best results are had by securing the brim 12 of the diaphragm to 100 the sheet metal member 2 throughout a part only of its width as shown in Fig. 4 as this gives the cone substantial freedom for axial movement.

The outer layer of veneer may have a 105 quick drying stain applied thereto to bring out and accentuate the graining in the wood thereby giving the loud speaker a very pleasing appearance. The stain employed should not have a tendency to clog the pores between the fibers of the wood. A very thin coating of wax may be applied over the stain to protect the veneer.

We have found that the wood veneer greatly improves the sound producing properties of the diaphragm giving a pleasing soft and mellow tone to the reproduced sound. The tone of the diaphragm approaches quite closely the tone of sound reproducing instruments made of wood, such 115 as a violin or cello. The appearance of the diaphragm gives the impression that it is made of solid wood. By making it of veneer as herein described the structural and other advantages of the usual paper or cloth diaphragm are retained and in addition we 120 obtain the advantages derived from the use of wood.

We claim:

1. A loud speaker having a conical vibratory diaphragm comprising a filler made of fibrous material, and at least two adherent layers of wood veneer on at least one side of said filler, the layers of veneer having their grains disposed at an angle to each other, each layer of wood veneer having an adherent layer of tissue paper and the layers of veneer being positioned with the tissue paper backings of each pair of veneer layers in contacting relation.

2. A vibratory diaphragm for loud speakers and the like comprising a filler made of fibrous material, and at least two adherent layers of wood veneer on at least one side of said filler, the layers of veneer having their grains disposed at an angle to each other, and each layer of wood veneer having an adherent layer of tissue paper.

3. A vibratory diaphragm for loud speakers and the like comprising a filler made of fibrous material, and at least two adherent layers of wood veneer on at least one side of said filler, the layers of veneer having their grains disposed at an angle to each other, each layer of wood veneer having an adherent layer of tissue paper, and the layers of veneer being positioned with the tissue paper backings of each pair of veneer layers in contacting relation.

4. A loud speaker having a direct acting

conical diaphragm made of fibrous material and at least one adherent facing of thin wood veneer on at least one side of said diaphragm.

5. A loud speaker having a direct acting conical diaphragm of fibrous material and at least one adherent facing of thin wood veneer on at least one side of said diaphragm, said wood veneer having a thickness ranging from about .00075 of an inch to about .001 of an inch.

6. A loud speaker having a direct acting conical diaphragm of fibrous material and at least one adherent facing of thin wood veneer on at least one side of said diaphragm, said wood veneer having an adherent layer of tissue paper.

7. A loud speaker having a direct acting conical diaphragm of fibrous material and at least one adherent facing of thin wood veneer on at least one side of said diaphragm, said wood veneer having a thickness ranging from about .00075 of an inch to about .001 of an inch and said facing or facings of wood veneer having an adherent layer of tissue paper of approximately the same thickness as the wood veneer.

In testimony whereof we affix our signatures.

ALFRED H. BARTSCH.

MARCUS C. HOPKINS.
